MATERNITY GARMENT

Jacob L. Alberts, Yonkers, Leon N. Alberts, New York, and Sydney S. Alberts, Yonkers, N. Y., assignors to Charma Brassiere Company, Inc., a corporation of New York.

Application December 28, 1949; Serial No. 135,496.

13 Claims. (Cl. 2-27)

1

This invention relates to foundation garments such as girdles, corsets, corselets, garter belts, brassières and the like and particularly to such garments of the maternity type and, in general, the object of the invention is to improve the construction of such maternity garments.

An object of the invention, also, is to provide a garment which, under normal conditions of the wearer, is conventional in function and has to appearance or fashion, but which is so constructed as to be extensible or enlargeable in the desired local areas to conform to the changing size and configuration of the body of the wearer during pregnancy.

Another object of the invention is to provide a maternity garment which meets the requirements of fashion, having no lacing or bracing or employing heavy materials, but which is made of the same attractive, light, soft, comfortable materials as other high fashion non-maternity garments.

Another object of the invention is to provide such a garment which is selectively extensible in the areas where enlargement is required and to provide such extensibility in such a way as to preserve proper and comfortable support and shaping of the body.

Another object of the invention is to provide for the convenient adjustment of the desired extensibility in such garments.

A further object of the invention is to provide a construction which permits the garment to be restored, later on, to the desired smaller size.

The invention will be described in connection with a maternity girdle and will be understood by reference to the accompanying drawings which show several modifications by way of example. In these drawings:

Fig. 1 is a front view of the preferred form of garment with a portion of the outer layer of the front section broken away;

Fig. 2 is a view somewhat similar to Fig. 1 but with the corners of the front section folded outward;

Fig. 3 is similar to Fig. 2 but with the upper front section folded downward and with one side folded out to expose the interior surface;

Fig. 4 is an enlarged vertical section taken on line 4-4 of Fig. 1;

Fig. 5 is a fragmentary perspective view of the upper righthand portion of the garment drawn to a greatly enlarged scale and with certain parts broken away;

Fig. 6 is a fragmentary view of the upper portion of the front section viewed from the inside;

2

Fig. 7 is a view similar to Fig. 6 with parts in a different position;

Figs. 8 and 9 are diagrammatic views in plan and side elevation respectively showing the gradational enlargement of the front section of the garment;

Fig. 10 is a view of a modification in front elevation similar to Fig. 1 but drawn to a somewhat larger scale;

Fig. 11 is a rear view of the garment shown in Fig. 10;

Fig. 12 is a development view of this garment looking at its inner surface;

Fig. 13 is a detail section taken on line 13-13 of Fig. 12 and drawn to an enlarged scale;

Fig. 14 is a view similar to Fig. 13 but with parts in different positions;

Fig. 15 is a fragmentary view similar to a portion of Fig. 12 showing a modified construction;

Fig. 16 shows another modification and is a view of the garment taken in vertical section and showing the inside of the front section;

Fig. 17 is a fragmentary view of the front section of the garment shown in Fig. 5 viewed from the inside but with the parts under tension;

Fig. 18 is a plan view of the parts shown in Fig. 17; and

Fig. 19 is a sectional view taken on line 19-19 of Fig. 18.

30 Referring now to these drawings and first to Figs. 1-9, inclusive, the garment here shown is constructed substantially throughout of a material having a horizontal stretch and also a vertical stretch, if desired, as is customary in certain types of girdles. In all forms of the garment wherein the material is referred to as elastic, extensible or stretchable it may have these properties through the inclusion of rubber or rubber-like material therein, or because of high twist of the yarn, special weaving or knitting of the fabric, bias cutting, etc.

Gradational control of the stretch of certain portions of the garment of Figs. 1-9 is provided in a manner to be described and in order to carry out the intent of the present invention. As shown in the drawings, the garment has a rear section 1, side sections 2 and 3, and upper and lower front sections 4 and 5, respectively. The lower front section 5 extends from the bottom of the garment upward somewhat less than one-half of the height of the garment and to the region of normal maximum diameter, it being understood that the garment is intended to encircle the body in the region of the hips. Upper front section 4 extends

55

from the region of maximum diameter to the top of the garment.

Rear section 4 of the garment is preferably allowed to stretch to the limit of its extensibility throughout its area although this may be controlled, if desired, whereas in the front and side sections the stretch is restricted in order to afford the desired support of the abdomen, that is to say, the elastic, extensible or stretchable material is not allowed to stretch to the limit of its extensibility; in fact, in the early part of the period of pregnancy the stretchable material is substantially prevented from stretching, or the stretching is greatly restricted, and the amount of extensibility is gradationally controlled by the wearer so as to cause the garment to conform to the changes in size and configuration of her body as the period progresses.

The elastic, extensible or stretchable material is indicated by reference numeral 6, and the gradational control of this fabric is accomplished by means of an additional layer of material which is either relatively non-stretchable, or substantially non-extensible such for example as woven fabric or one-way stretch material which does not stretch in the direction of stretch of the stretchable fabric. This added layer may be placed on either the outside or the inside of the garment, that is, of the material 6. Preferably, however, this added layer 7 is placed on the inside and forms a lining for those portions of the garment over which it extends. The stretching control layer 7 preferably extends throughout the upper front section 4 of the garment and is secured to section 4 only at the opposite sides, that is to say, the opposite side edges of control layer 7 are permanently secured to the opposite side edges of the elastic material 6 which forms section 4, these edges being indicated at 8 and 9, respectively.

The two layers of material may be secured together in any suitable way as, for example, by means of one or more vertical lines of stitching as shown more particularly in Fig. 5. It will be understood, of course, that in this specification the word "vertical" is used merely to mean in the general up and down direction in contrast to horizontal. Control material 7 is provided with a series of vertical tucks or sewed folds 10, each fold being held by a vertical line of stitching 11. As shown in Fig. 1, these tucks are located in the central region of control layer 7, although they may be otherwise arranged, as in two areas, shown in Fig. 16, one at each side of a central panel 12 which, however, is of freely extensible fabric. Also, if desired, the tucks may be spaced across the entire width of control layer 7 and the individual tucks may be made of any suitable width. Also, tucks 10 extend throughout the vertical height of control layer 7, although, if desired, some of these tucks may be shorter than others in order to shape the garment as desired. Thus, as shown in Fig. 1, the center tuck extends only about half way from the top to the bottom of upper front section 4.

Upper front section 4 is releasably attached along its side edges 8 and 9 to the corresponding edges of side sections 3 and 2, respectively, by any suitable attaching means, such for example as the hooks 13 and eyes 14. Two rows of eyes 14 are preferably provided along the edges of side sections 3 and 2, these two rows converging into a single row at their lower ends.

The width of control layer 7 with all of its tucks intact is substantially equal to the un-

stretched width of the elastic material 6 across the face of upper front section 4, and under these circumstances this area of fabric 6 is substantially prevented from stretching. Hence, when the garment is placed about the body with hooks 13 on both sides of section 4 fastened to the outer rows of eyes 14, the maximum restriction of the body will be afforded. In other words, this provides the smallest size of the girdle. As the conditions of the body change and comfort demands greater freedom the hooks may be shifted to the inner row of eyes, first on one side and then on the other.

Thereafter, in order to attain greater expansion for the abdomen the stitching lines 11 are successively removed thereby gradationally increasing the effective width of control layer 7 and permitting the elastic material 6 of upper front section 4 to stretch or extend to a greater and greater degree. For example, referring to Fig. 6 the distance "a" indicates diagrammatically the width of the garment across the top before any of the tucks have been removed. In Fig. 7, however, the line of stitching 11 for the central tuck 10 has been removed and the line of holes in the control layer 7 which were formerly occupied by the line of stitching are indicated at 15. These lines have separated one half the width of the tuck from the centerline of the garment, thus allowing the width of the garment to increase by this much on each side as is indicated by the dimension "A."

The lower front section 5 of the garment is also provided with a layer of non-stretchable material which is indicated at 16. This layer preferably also has tucks 16a either full or part length and so distributed as to control the extensibility or stretching of the elastic material 6 of this portion of the garment, as desired. At the V-section indicated by numeral 17 in Figs. 1 and 2, the material 16 is removed so as to allow uncontrolled stretching of the fabric 6 within this triangular area. The restriction of the stretching of the garment throughout lower front section 5 in combination with the controlled stretchability of upper front section 4 as above described, enables the front portion of the garment to afford a shelf-like support to the lower portion of the abdomen. This is indicated diagrammatically in Fig. 9. The series of dotted outlines in this figure and in Fig. 8 show the gradational extension of the front section of the garment as a number of the tucks 10 are individually and successively removed.

In addition to the gradational control of the front section of the garment, the garment is also preferably provided with a similar control for its side sections 2 and 3. These sections are each provided with an inner control layer which is similar to control layer 7, but which is shown as only a single sewed fold or tuck 19 which is held in place by a line of vertical stitching 20. The control material 18 extends the full length of the garment from top to bottom but may be divided into sections, if desired, and it will be understood also that additional tucks may be added, if desired, and that some of these may extend only a part of the height of the garment. It will be understood that when the line of stitching 20 has been removed the effective horizontal length of the control material 18 is increased so as to allow the elastic fabric 6 to stretch to a greater extent. The effect of removing this line of stitching is indicated by the dotted lines in Figs. 8 and 9 at the rear portion

5

It will be understood that instead of making the garment of Figs. 1-9 so that the upper front portion 4 folds downwardly to enable the garment to be put on and taken off, the hook and eye connections on one side may be continued to the bottom of the garment so as to change it from the step-in type to the type which is applied by wrapping around the wearer.

In Figs. 10-15, inclusive, there has been illustrated a garment of the wrap-around type which also differs from the garment previously described in certain respects. The front panel section is indicated at 21 and this is made preferably of fabric which is stretchable in the vertical direction only except for the V-shaped insert 22 at the bottom which is stretchable in both directions. It could be made, however, of two-way stretch fabric, and it could also be of non-stretch fabric. The rear section is preferably made of two portions, the lower portion 23 which extends within a few inches of the top, being preferably made of fabric which stretches in the vertical direction only, and the upper section 24 of fabric which is stretchable in the horizontal direction only. The two side sections 25 and 26, however, are preferably made of fabric which is stretchable in both directions. The garment may be provided with finishing tapes 27 and 28 along the top and bottom margins, respectively, but these tapes are so made that they do not change the character of the respective garment sections as to horizontal stretchability. In other words, front section 21 is preferably non-stretchable in the horizontal direction throughout its length from the extreme bottom edge to the extreme top edge, except for the triangular insert 22. Likewise, the lower rear section 23 is preferably non-stretchable horizontally to its extreme lower edge, whereas the upper rear section 24 is horizontally extensible all the way to its upper edge including the tape 27. Further, the sections of tapes 27 and 28 which are applied to the side garment sections 25 and 26 are horizontally extensible so that no restriction in horizontal extensibility is produced by the finishing tapes 27 and 28.

The garment is held in place by any suitable fastening means such as a row of hooks and eyes applied to the terminal vertical edges 29 and 30, respectively. As indicated in Fig. 12 there is preferably a double row of eyes which converges into a single row slightly below the mid-section of the garment so as to provide for an adjustment similar to that described in connection with the garment of Figs. 1-9, inclusive.

In the modified form of garment substantially the entire front section 21 is made non-stretchable horizontally and the stretch-control material is applied to the side sections 25 and 26, the rear section 23 also being non-extensible horizontally except in a narrow region along the top thereof. The stretch-control material 7a in the form of woven fabric or any suitable material is shown as applied over about one-half of the width of each of the two side sections 25 and 26 as shown in Fig. 12, preferably the rear half portions of the side sections so as to form lateral or horizontal continuations of the rear sections 23 and 24. Material 7a may, however, be applied over less or more than half the width of sections 25 and 26.

As indicated in Figs. 12 and 13, the control material 7a is provided with one or more full length tucks 31 and with one or more tucks 32 which extend less than the full vertical length

6

of the control material. It will be understood that these tucks are held in place by removable lines of stitching 33 and that gradational control of the extensibility of sections 25 and 26 is obtained by successively removing these lines of stitching whenever it is desired to enlarge the garment, or the upper portion thereof. Thus, in Fig. 14 one of the lines of stitching 33 has been removed and the tuck which it held has unfolded thereby extending the effective horizontal width of the control material 7a, thus permitting the elastic fabric 6 of side section 26 adjacent to this material to stretch to a greater extent.

15 The nonstretchable character of front section 21 in the horizontal direction gives the desired support to the abdomen, whereas a considerable yielding effect is provided by the uncontrolled stretchable areas of side sections 25 and 26, the remaining areas of these sections which are subject to the gradational control just described affording a means of successively enlarging the garment as desired. Stretchability of the material of front section 21 in the vertical direction facilitates the formation of the shelf support previously referred to in connection with Figs. 1-9.

In Fig. 15 a modified arrangement of the control material 7a for sections 25 and 26 is shown. Instead of applying the control material in a single continuous strip from the top to the bottom of the garment as in Fig. 12, it is applied in several separate sections 7ax, 7ay, and 7az. The tucks 34 may be employed in all three of these sections or they may be omitted altogether or shortened in any one of the sections, for example, the lowest section 7az. The sections of control material wherever located in this garment or in the garment of Figs. 1-9 may be subdivided in this manner, if desired.

The modification shown in Fig. 16 was briefly referred to in connection with Figs. 1-9, inclusive. The gradational control of the extensibility of the elastic fabric of the upper front section 4a is obtained in the same way as described in connection with Figs. 1-9, the only difference between sections 4a and 4 being that the central portion, or panel, 12 of section 4a is left freely elastic or stretchable, whereas in section 4, permanently non-extensible bordering panels (considering the two layers 6 and 7 together) are located on each side of the central portion of the material 7 which is provided with the tucks 10. In Fig. 16, the tucks 10a are comprised in bordering panels disposed on each side of the central, freely stretchable panel 12.

The lower front section 5a of Fig. 16 differs from section 5 of Figs. 1-9 in that provision is here made for gradational control of the vertical stretch and, to a lesser degree, the horizontal stretch of the fabric 6 of this lower section. For this purpose a layer 35 of stretch-control material extends from side to side of the lower front section 5a, being stitched to the stretchable elastic material of this section at the sides as indicated by the dotted lines and also along the bottom edge of the garment. Stretch-control material 35 has a deep notch 36 cut into its upper edge and the material is stitched to the stretchable elastic material along the horizontal lines 37 at each side and along the vertical lines 38 at the opposite sides of the notch. From the bottom of the notch a tongue projects upwardly and is stitched to the stretchable elastic fabric along the horizontal line 39 and is provided with an in-

determinate series of tucks 40, two being shown. The side edges of this tongue portion within notch 36 are unattached to the stretchable elastic fabric. Below this tongue portion and in line with the edges of notch 36 are two tucks 41, preferably of the tapering or graduated type.

When it is desired to let out lower front section 5a, the two vertical tucks 41 are first removed by cutting their holding stitches. This allows the stretchable elastic fabric to stretch horizontally to a greater extent. It will be understood that additional vertical tucks of the straight or graduated type and substantially parallel to tucks 41 may be employed, if desired, to give a greater horizontal let-out. When it is desired to let out front section 5a still further, one or more of the horizontal tucks 40 may be removed which allows the stretchable elastic material to stretch to a greater extent in the vertical direction.

In Figs. 17, 18 and 19, the form of stitching is illustrated which is preferred to employ in stitching all of the tucks which have been referred to in the above description. Fig. 17 shows a single vertical tuck 10 as illustrated, for example, in Fig. 5 viewing the tuck from the inside of the garment and considering that the stretch-control material 7 has been placed under tension as it is when the garment is worn. Fig. 18 is a view looking down on the edge of this tuck and the sectional view, Fig. 19, shows the relative positions of the two threads forming the stitching. One of the threads, for example thread 42, lies in a substantially straight line against the inside surface of material 7 adjacent the right bend 43 of tuck 10. The second thread 44 passes first through the left bend 45 of tuck 10, thence through right bend 43 and around thread 42, thence back through bends 43 and 45, this cycle being repeated to form a series of loops 46 which extend across the space between the tuck bends 43 and 45 and around the thread 42. This provides a form of stitching which, when the stretch-control material 7 is placed under tension, is very readily removed. This can be done either by severing loops 46 throughout the length of the tuck in the space between bends 43 and 45. Or it can be done without tension by freeing the opposite ends of thread 42, for example, by severing this thread at each end and then pulling the thread out of the loops 46. Thereafter, thread 44 may also be freed at each end and pulled out with a single motion.

The garment of the present invention affords the support which is desired in a maternity garment without the use of lacings or of rigid stays and with the advantage that the garment can be styled as desired and that it can be adjusted in size from time to time while retaining the yielding support given by stretchable elastic or resilient fabric.

It will be understood that the construction of the invention as described above, if desired, can be applied to garments of the panty-girdle type and to corsets, corselets, garter belts, brassieres and the like, as well as to the garments described. In a panty-girdle the stretch-control material is preferably omitted from the lower section. The garment of the invention can be restored to its original condition after full use is made of the gradational control of stretchability and size, by replacing the tucks in the control material or by inserting a layer of non-stretchable material of appropriate width to give the size of garment desired.

The invention has been set forth in connection

with several modifications. It will be understood, however, that additional changes may be made in the construction of the garment or the arrangement of its parts without exceeding the spirit and scope of the invention as set forth in the appended claims.

We claim:

1. A garment of the class described constructed and arranged to encircle the body and having at least one section comprising two layers, one of said layers being extensible in one direction and the other layer being of material which is non-extensible in the direction of extension of said extensible layer, said non-extensible material being secured at its opposite side edges to said extensible layer and having portions normally not forming an effective part of said non-extensible layer, said portions being selectively releasable to form an effective part of said non-extensible layer to increase the effective dimension thereof in the direction of extension of the extensible layer, whereby the extension of said extensible layer may be gradationally controlled.

2. A garment of the class described constructed and arranged to encircle the body and having at least one section comprising two layers, one of said layers being of stretchable fabric and the other layer being of material which is relatively non-extensible in the direction of stretch of said stretchable layer, said non-extensible material being secured at its opposite side edges to the stretchable fabric and containing at least one sewed fold disposed to render the effective dimension of said non-extensible material between said side edges approximately the same as that of the adjacent layer of unstretched stretchable fabric, the stitching of said fold being removable to increase said effective dimension and thereby provide for an increase stretch of said stretchable fabric.

3. A garment of the class described as set forth in claim 2 in which the stitching is formed in loops which are elongated crosswise of the folds causing the adjacent bends of the folds to separate when placed under tension so that the stitches can be readily severed without cutting said fold bends.

4. A garment of the class described as set forth in claim 2 in which the stitching is formed with a series of threaded loops extending from one bend of a fold to the opposite bend thereof, thence through the material and around a second thread, said second thread lying along the surface of said material substantially in a straight line and unlooped about the first thread.

5. A garment of the class described constructed and arranged to encircle the body, at least one section thereof being of fabric which is stretchable both horizontally and vertically, a layer of material secured at its side edges to a portion of said stretchable section, said layer being non-stretchable in at least one direction and having at least one section releasable to increase the effective dimension of said layer in its non-stretchable direction to permit an increase of the stretch of the stretchable fabric between the places where said non-stretchable layer is secured thereto, and a second layer of material non-stretchable in at least one direction secured at its side edges to a second portion of said stretchable section, said second layer of non-stretchable material having sections releasable to increase the effective dimension of said second layer of non-stretchable material to permit

an increase of the stretch of the stretchable fabric between the places where said non-stretchable layer is secured thereto, the direction of stretch control of said second layer of non-stretchable material being at an angle to the stretch control of said first layer of non-stretchable material.

6. A garment of the class described as set forth in claim 5 wherein the first-mentioned section is in the upper portion of the garment and in which the layer of non-stretchable material of said section is divided into two spaced areas leaving a central panel of freely stretchable fabric between said areas.

7. A garment of the class described as set forth in claim 5 wherein the second-mentioned section is in the lower portion of the garment and in which the strength control layer for said section provides control in the vertical direction for the stretchable fabric immediately below said central panel.

8. A garment of the class described as set forth in claim 5 wherein the second-mentioned section is in the lower portion of the garment and in which the layer of stretch control material for said section provides a stretch control in both the vertical and horizontal directions.

9. A garment of the class described constructed and arranged to encircle the body and including front and side sections, said front section being releasably attached along vertical lines to at least one of said side sections by means of a double row of fastening devices, said front section being made of stretchable fabric, and a layer of non-stretchable material having sections releasable to increase the effective dimension of said layer in one direction secured at its side edges to said front section, whereby changes in the size of the garment can be effected both by said double row of fastening devices and by releasing said releasable sections.

10. A garment of the class described constructed and arranged to encircle the body, substantially the entire garment being made of stretchable fabric, the lower front section of the garment from the bottom upward having a layer of relatively non-extensible material provided with means to control the stretch of said lower front section, the side edges of said layer being secured by a vertical seam to the sides of the garment, and the upper front section of the garment extending upwardly from said lower section substantially to the top of the garment being releasably secured to at least one side section of the garment, and a layer of relatively non-extensible material extending throughout said upper front section and having means to control the extensibility of said upper front section, the upper and lower edges of said last-mentioned layer of non-extensible material being attached to said upper front section to selectively control the extensibility of said section.

11. A garment of the class described, at least one section of which is composed of two layers, one of said layers being of stretchable material and the other of said layers being of non-stretchable material having at least one section which normally does not form an effective part of that layer, said section being releasable to form an effective part of the non-stretchable layer to increase the effective dimension thereof to permit the stretchable layer to be stretched a greater distance to increase a dimension of the garment, said layers being secured together along the side edges of said section and substantially perpendicular to the direction of said change in dimension.

12. A garment of the class described, at least one section of which is composed of two layers, one of said layers being of stretchable material and the other of said layers being of relatively non-stretchable material containing a series of releasable sewed folds extending at right angles to the direction of stretch of said stretchable layer, said layers being secured together along the side edges of said section substantially parallel to said folds.

13. A garment of the class described having a front section comprising a central panel and two bordering panels, one on each side of the central panel, said central panel being stretchable in at least one direction and said bordering panels being composed of two layers secured together along the side edges and to said bordering respective panels, one of said layers being stretchable in at least one direction and the other of said layers being non-stretchable and having sections normally not forming an effective part of said non-stretchable layer, said portions being selectively releasable to form an effective part of said non-stretchable layer to increase the effective dimension thereof in the direction of stretch of the stretchable layer to provide gradational control of the stretch of said bordering panels by the wearer, whereby said panels can be stretched to successively greater extents to increase a dimension of the garment.
